ELECTRIC LIGHTING FIXTURE

Harry D. Hain, Cleveland, Ohio, assignor to
Railley Corporation, Cleveland, Ohio, a corpora-
tion of Ohio

Application October 28, 1935, Serial No. 47,058

5 Claims. (Cl. 240—128)

This invention relates to a shade fixture adapted to be used in connection with a plurality of lamps and has for its principal object to provide a shade element adapted to enclose a plurality of adjacently positioned lamp and receptacle units and to abut against a surface from which such units project and in surrounding relation thereto and which shall be provided with overcentering connecting means between a plurality of lamps and the shade whereby the shade may be attached while its upper edge is in spaced relation to a ceiling or similar surface and then pushed toward such surface and held thereagainst by such connecting means. It is to be understood of course that it is immaterial whether the lamps enclosed by the shade element be carried by a single fixture or by a plurality of receptacles positioned close together.

A further object is to provide a novel yieldable connecting means and one which will afford a light but sufficiently rigid connection to hold the shade in proper relation to the lamps.

With the foregoing and other objects in view, the invention consists in all the novel features of construction hereinafter described and illustrated in the accompanying drawing wherein Fig. 1 is an elevation of a shade positioned in contact with a ceiling and showing the lamps, receptacles and connecting means in skeleton form and in dotted lines; Fig. 2 is a similar elevation showing the shade attached to the lamps but not yet moved into contact with the ceiling or similar supporting surface; Fig. 3 is a plan view of the shade and connecting means disconnected from the lamps; and Fig. 4 is a fragmentary detail elevation corresponding substantially to the line 4—4 of Fig. 3.

In the drawing, the numeral 10 indicates a ceiling, wall or other surface from which lamp and receptacle units project and which are adapted to be enclosed by the shade 11. In the drawing, I have illustrated adjacently positioned receptacles 12 having electric bulbs 13 received therein. These are designated lamp and receptacle units. Such expression, however, is intended to include a single element instead of two elements 12 having therein a plurality of sockets whereby a plurality of electric bulbs are received in spaced relation to each other but sufficiently close to be enclosed by the shade 11.

The shade 11 may be provided with wire rims 14 between which extends sheet material such as parchment and attached to one of the rims 14 are U-shaped elements 15 to which are connected by suitable eyes spaced wires 16. A cross

piece 17 may connect each of the pairs of wires 16 adjacent the U-shaped elements 15 and may form a stop for engagement with springs 18 which are received on the element 16. The element 16 may terminate in eyes 19 and may receive eyes 20 attached to the rings 21 which are of a size to receive the necks of the electric bulbs 13. The use of spaced elements 16 rigidly connected together for connecting the rim 14 to the rings 21 results in a rigid construction which will not allow the shade to move to either side of the line adjoining the two lamps.

From the foregoing it will be apparent that the fixture may be readily connected by holding one of the rings 21 and placing the neck of one of the electric bulbs therethrough and into the receptacle 12, doing likewise in the case of the other ring and bulb and then pushing the shade upwardly until the connecting element overcenters and holds the same firmly against the ceiling, wall or similar surface as indicated in Fig. 1.

From the foregoing it will be obvious that I have provided a device which is well adapted for its intended purpose and while I have shown and described the present preferred embodiment of my invention, I wish it understood that the same is not limited to the details shown but only in accordance with the appended claims and the prior art.

Having thus described my invention, what I claim is:

1. A shade fixture for a plurality of lamps comprising a shade element adapted to enclose a plurality of adjacently positioned lamp and receptacle units and to abut against a surface from which such units project and yieldable means resiliently connecting said units with said shade element, the points of connection of said yieldable means to said units being more remote from said surface than the point of connection of the same to said shade when said shade is in normal contact with said surface, said yieldable means including a member having an opening adapted to receive an electric bulb, spaced connecting members connecting to said member at spaced points and to a rim of said shade at spaced points, and spring means tending to effectively lengthen said connecting members.

2. A shade fixture for a plurality of lamps comprising a shade element adapted to enclose a plurality of adjacently positioned lamp and receptacle units and to abut against a surface from which such units project and yieldable means resiliently connecting said units in overcentering relation with said shade element, said yieldable

means including a member having an opening adapted to receive an electric bulb, spaced connecting members connecting to said member at spaced points and to a rim of said shade at spaced points and spring means tending to effectively lengthen said connecting members.

3. A shade fixture for a plurality of lamps comprising a shade element adapted to enclose a plurality of adjacently positioned lamp and receptacle units and to abut against a surface from which such units project and yieldable means resiliently connecting said units with said shade element, the points of connection of said yieldable means to said units being more remote from said surface than the point of connection of the same to said shade when said shade is in normal contact with said surface, said yieldable means each including a ring adapted to receive an electric bulb, connector means connected to a rim 20 of said shade at spaced points and to said ring at spaced points and including elongated elements slidably connected to said ring and springs surrounding said elongated elements and compressible to permit overcentering of said yieldable means.

4. A shade fixture for a plurality of lamps comprising a shade element adapted to enclose a plurality of adjacently positioned lamp and receptacle units and to abut against a surface from

which such units project and yieldable means resiliently connecting said units in overcentering relation with said shade element, said yieldable means each including a ring adapted to receive an electric bulb, connector means connected to a rim of said shade at spaced points and to said ring at spaced points and including elongated elements slidably connected to said ring and springs surrounding said elongated elements and compressible to permit overcentering of said yieldable means.

5. In combination, a shade and mechanism for holding the same against a surface in surrounding relation to fixed electric lighting means projecting from said surface, said mechanism comprising a plurality of elongated elements, each pivoted at one end to said shade adjacent the edge thereof which is to be held against said surface and adapted to extend radially inwardly of said shade at an angle to said surface and to engage a portion of said electric lighting means, said elements being circumferentially spaced about said shade and being compressible to reduce their effective lengths whereby when the shade is moved toward and from said surface said elements may over-center their points of engagement with said electric lighting means.

HARRY D. HAIN.
